UNITED STATES PATENT OFFICE.

GEORGE H. WILLARD, OF HOPEDALE, MASSACHUSETTS, ASSIGNOR TO DRAPER CORPORATION, OF HOPEDALE, MASSACHUSETTS, A CORPORATION OF MAINE.

FILLING-REPLENISHING-LOOM THREAD CONTROL WITH BOBBIN CLEANING.

Application filed April 12, 1927. Serial No. 183,046.

This invention relates to filling replenishing looms and is more particularly directed to the thread control with bobbin cleaning attachment for withdrawing the thread from 5 the shuttle box on replenishment of filling and cleaning the bobbin of waste yarn.

In that type of filling replenishing looms wherein replenishment of filling is effected by a change in the filling carrier or bobbin 10 in the shuttle, it is desirable to withdraw the filling end of the outgoing filling carrier from the shuttle to prevent such end being carried into the shed and to clean the bobbin of waste yarn thereupon after the 15 bobbin has been ejected from the shuttle.

An important feature of the present invention therefore consists in an attachment for filling replenishing looms whereby the filling end extending into the shuttle from the 20 ejected filling carrier is withdrawn therefrom and the waste filling upon the filling carrier or bobbin is unwound or withdrawn therefrom during the operation of the loom following replenishment.

25 In accordance with the present invention the filling carrier which is ejected from the shuttle on replenishment of filling is discharged into a bobbin receiver and the end of the filling leading from the ejected carrier is withdrawn from the shuttle and unwound from the ejected filling carrier or bobbin.

The invention and new combination of parts and novel features thereof will best be 30 made clear from the following description and the accompanying drawings of one good form thereof.

In the drawings:

Fig. 1 is a perspective view of portions of a 35 loom having the present invention applied thereto and showing some of the parts broken away;

Fig. 2 is a transverse section through the bobbin receiver and the parts associated therewith, and showing the bobbin positioned for removal of filling leading therefrom;

Fig. 3 is a section on the line 3—3 of Fig. 2; and

Fig. 4 is an enlarged sectional detail showing the clutch connection between the bobbin cleaning device and its actuating shaft.

The loom frame 1 may be of usual construction and rising from the breast beam 2 55 is the hopper or magazine stand 3 contain-

ing a series of filling carriers or bobbins 4 supplied with filling. Extending laterally from the feeler stand is the stud or dead shaft 5 on which is mounted the transerrer 6, the downwardly extending arm 7 of 60 which is associated with the dog 8 which on detection of substantial exhaustion of filling in the shuttle is positioned to be engaged by a bunter on the lay to actuate the transerrer, as usual in this general character 65 of loom.

Secured to the loom frame 1 is a bracket 9 on which is supported a bobbin receiver 10 into which the ejected filling carrier is thrown on replenishment of filling. The 70 bobbin receiver 10 has an open bottom 11 below which is located the bobbin can 12 for receiving the cleaned bobbins, in a manner later to be described.

Extending transversely of the bobbin receiver 10 is the bobbin cleaner and filling end withdrawing device. As indicated in the present instance of the invention, the bobbin cleaner comprises a shaft 13, one end of which extends laterally through the side 80 of the bobbin receiver 10, and is provided with a pulley 14 by which the bobbin cleaner may be given rotary movement from some going part of the loom. As shown, the bobbin cleaner shaft 13 is driven by a belt 15 85 which passes around a pulley 16 mounted on the cam shaft 17 and preferably, though not necessarily, formed as part of the hub portion of the pick cam 18, the construction being such that the bobbin cleaner shaft 13 90 will be continuously rotated during the loom operation.

Mounted on the shaft 13 is the bobbin cleaner 19 which may be of general cylindrical form and have a roughened exterior 95 surface, shown in the present instance as provided by wire teeth 20. The bobbin cleaner 19 is operatively associated with the shaft 13 by means of a clutch which, as shown, comprises a series of yieldable fingers 21, 100 Fig. 4, embraced by a spring 22 and adapted to engage the end portion 23 of the bobbin cleaner 19, so that on rotary movement of the shaft 13 the bobbin cleaner will be rotated.

The bobbin cleaner 19 extends through the sides of the bobbin receiver 10 and in order to confine the thread or yarn between the sides of the bobbin receiver, guards 24 and 25 are preferably employed, the guard 24 110

substantially enclosing the clutch mechanism between the shaft 13 and the bobbin cleaner 19, as indicated more clearly in Fig. 4.

5 Mounted in the bobbin receiver 10 below the bobbin cleaner 19 is the bobbin positioning device having compartments, each of which is adapted to receive a bobbin to be cleaned and retain it in bobbin cleaning position, so that the bobbin may be cleaned of waste thread or yarn while separated from bobbins previously cleaned.

10 The bobbin cleaning device comprises a shaft 26 extending transversely of the bobbin receiver below the bobbin cleaner 19 and may be conveniently journaled in the side portions of the bobbin receiver, as indicated at 27.

15 Extending radially from the shaft 26 are the wing portions 28 between each of which is formed a compartment for receiving a bobbin to be cleaned and positioning the bobbin for cleaning purposes.

20 In the present instance of the invention, the wings 28 are mounted on a sleeve 29 secured to the shaft 26 so that on rotation of the shaft 26 the bobbin positioning device may be moved to positively discharge a cleaned bobbin from one compartment and 25 position another compartment for the reception of the next bobbin to be cleaned following replenishment of filling.

25 One end of the shaft 26 extends beyond the side portion of the bobbin cleaner, as indicated in Figs. 1 and 2, and means are provided for imparting to the bobbin positioning device a step-by-step rotary movement on each successive replenishment of filling, to positively move the bobbin previously positioned for cleaning purposes and present 30 another compartment for the reception of the next bobbin to be cleaned.

35 As one good form of means to this end, the shaft 26 is provided with a toothed wheel or ratchet 30, the teeth 31 of which are adapted to be engaged by an operating pawl 32 having a tooth 33, so that on endwise movement of the pawl 32 the bobbin positioning device will be given its rotary movement.

40 Mounted on the loom frame is the transverse or change shaft 34 having depending therefrom the actuating arm 35 to the lower portion 36 of which is pivoted the pawl 32, the construction being such that on call for 45 replenishment of filling when the transverse or change shaft 34 is given its rocking movement, as usual, the actuating arm 35 will be moved to operate the pawl 32 and effect rotary movement of the bobbin positioning device.

50 When a bobbin with waste thread or yarn thereon is ejected from the shuttle by the incoming filling carrier under the action of the 55 transferrer, it will be thrown into the bobbin

receiver 10, with the trailing end *a* of the waste thread or yarn thereon extending over and in contact with the bobbin cleaner 19, and to facilitate movement of the ejected filling carrier into the compartment of the bobbin 70 positioning device, the bobbin receiver 10 is provided with a deflector 37, the lower end portion 38 of which is closely adjacent to one side of the compartment positioned for the reception of the ejected filling carrier or 75 bobbin. The deflector 37, in the present instance of the invention, may be conveniently formed of metal and have a bend 39 to engage a dead shaft or pin 40 extending transversely of the bobbin receiver, and in order to 80 maintain the deflector 37 in its desired position and yet permit yielding movement thereof, the deflector 37 below the bend 39 is provided with a yielding stop 41 which normally rests upon the side of the bobbin 85 receiver 10, the construction being such that the ejected filling carrier will be thrown into the bobbin receiver, engage the deflector 37 and be by it directed into the compartment of the bobbin positioning device, as indicated 90 in Fig. 3, so that the trailing end *a* leading from the waste thread or yarn on the bobbin will engage the bobbin cleaning device 95 19 and be by it unwound from the bobbin positioned by the bobbin positioning device.

95 When filling replenishment is being effected and a discharged bobbin is thrown from the shuttle, it is desirable that the end leading from the ejected filling carrier or bobbin 100 shall be removed from the shuttle eye and shuttle box to thereby prevent the end of the filling being drawn into the shed, and in connection with the bobbin cleaning device the present invention provides means for 105 withdrawing the end from the shuttle eye and shuttle box so that said end without breakage may be wound upon the bobbin cleaning device as the bobbin is being cleaned.

110 The thread controller for effecting the above purpose may be of any usual type, but inasmuch as the end of filling that is withdrawn from the shuttle eye may extend over a part of the said controller and engage the 115 bobbin cleaning device, a loop may be formed in the end of the filling above the bobbin cleaning device, and in accordance with the present invention, provision is made for the disengagement of the said loop from the 120 thread controller in case of such contingency.

125 As hereinbefore noted, the thread controller for withdrawing the end of filling from the shuttle box and shuttle may be of any appropriate character, but in accordance with the present invention, the thread engaging member of the said controller is extended laterally and downwardly so that in case of the formation of a loop over the said member of the controller, the action of the bobbin 130

cleaner upon both parts of the thread will cause the loop to slip downwardly over the end of the laterally and downwardly extending member of the thread controller.

5 As shown in the the present instance of the invention, the thread controller comprises a sleeve 42 which is connected to the hub portion 43 of the transerrer, and such sleeve 42 has a downwardly extending arm 44 carrying a pin 45 connected by a link 46 to a carrier 47 in which is mounted for movement towards and from the front of the loom a slide 48. A spring 49 normally acts upon the slide 48 to maintain it in rearward position. Pivotally mounted at 50 on the slide 49 is the laterally and downwardly extending filling engaging member 51, which acts to permit the loop of thread which may be formed thereon to slide downwardly and over the end of the member 51 should both portions of the thread be engaged by the bobbin cleaning device 19.

It is sometimes desirable to impart a frontward movement to the filling engaging member 51 of the controller on replenishment of filling to insure withdrawal of the filling from the shuttle and shuttle box, and as will be noted from the construction described, the downward movement of the 30 transerrer will effect frontward movement of the controller to withdraw the filling end from the shuttle and shuttle box. The slide 48 is provided with an opening 52 which engages a guide 53 in the carrier 47 in order to 35 direct its movement towards and from the front of the loom. Should the filling engaging member 51 contact with the lay or be otherwise engaged during the loom operation, the spring 49 will permit a frontward yielding movement of the filling engaging member 51 which may also pivot around its connection 50 with the slide 48.

During weaving operation the filling engaging member 51 is retained in position such that an ejected filling carrier will pass frontwardly thereof on replenishment of filling, and the frontward movement of the filling engaging member will whip the filling from the shuttle and shuttle box. When the ejected filling carrier is received into the bobbin receiver 10, the trailing end of thread *a* will be positioned for engagement with the bobbin cleaner 19 when the ejected filling carrier has been received into the compartment of the bobbin positioning device, so that both ends of the thread—that extending upwardly to the engaging member 51 and that extending downwardly to the bobbin positioned by the compartment of the 55 bobbin positioning device, will be simultaneously wound upon the bobbin cleaner 19, and should a loop of thread be formed about the thread engaging member 51 of the thread controller, the loop thereof will 60 be moved downwardly on the laterally ex-

tending and inclined filling engaging member until upon reaching the end thereof under the pull of the bobbin cleaner, it will be disengaged therefrom without breakage.

As hereinbefore described, the bobbin positioning device having the compartments for positioning a bobbin for cleaning purposes, is given a step movement on each replenishment of filling, to positively move the cleaned bobbin from its cleaning position 75 and allow it to drop into the bobbin can beneath, and in order to prevent movement of the bobbin positioning device during normal weaving operations, a lock is provided to prevent movement of the bobbin position- 80 ing device until call for replenishment of filling.

In the present instance of the invention, this lock is formed as a spring arm 54 having an end portion which engages recesses 85 formed in a locking member 55 secured for rotative movement to the bobbin positioning device, as indicated in Figs. 1 and 2. The weight of the pawl 32 resting on the ratchet wheel 30 also contributes to lock the bobbin 90 positioning device from movement until call for replenishment of filling.

From the construction described it will be apparent that the present invention provides a simple and effective means for not 95 only cleaning the waste yarn or thread from ejected filling carriers, but likewise to whip the end of thread from the shuttle and shuttle box and to wind such upwardly extending end onto the bobbin cleaner during 100 the bobbin cleaning operation.

The bobbin positioning device with its compartments for positioning the bobbin for the cleaning operation and for thereafter positively removing the cleaned bobbin from 105 bobbin cleaning position with the substitution of another compartment to receive the next bobbin to be cleaned, may be variously contrived, but the rotary winged positioning device forms a compact and readily adjustable means to this end.

What is claimed is:

1. In a filling replenishing loom, the combination of a filling end controller for withdrawing the outgoing filling end from the 115 shuttle on replenishment of filling, a bobbin receiver, a bobbin cleaner for withdrawing the filling end from the controller and unwinding the filling from the bobbin, bobbin positioning means below the bobbin cleaner having bobbin compartments for holding a bobbin while it is cleaned, and means for moving the bobbin compartment on replenishment of filling to positively move the cleaned 120 bobbin from the positioning means.

2. In a filling replenishing loom, the combination of a filling end controller for withdrawing the outgoing filling end from the shuttle on replenishment of filling and having a downwardly extending filling engaging 125

member, a bobbin receiver, a bobbin cleaner for withdrawing the filling end from the controller and unwinding the filling from the bobbin, bobbin positioning means below 5 the bobbin cleaner having bobbin compartments for holding a bobbin while it is cleaned, and means for moving the bobbin compartment on replenishment of filling to positively move the cleaned bobbin from the 10 positioning means.

3. In a filling replenishing loom, the combination of a filling end controller for withdrawing the outgoing filling end from the shuttle and having a laterally and downwardly inclined filling engaging member, a bobbin receiver, a bobbin cleaner for unwinding the filling from the bobbin and acting on the filling leading over the downwardly inclined filling engaging member to remove 15 the filling therefrom.

4. In a filling replenishing loom, the combination of a filling end controller having a laterally and downwardly extending filling engaging member, means for imparting a 20 frontward movement thereto on replenishment of filling to withdraw the outgoing filling end from the shuttle, a bobbin cleaner for removing waste filling from the bobbin and acting on the filling leading over the 25 downwardly extending filling engaging member of the controller to remove the filling therefrom.

5. In a filling replenishing loom, the combination of a bobbin receiver, a rotating bobbin cleaner for withdrawing the filling from the discharged bobbin, a bobbin positioning member below the bobbin cleaner having a plurality of bobbin compartments for holding a discharged bobbin while it is being 30 cleaned that the rotating bobbin cleaner may act upon the filling between the compartment and shuttle box, and means for moving the bobbin compartment on call for replenishment of filling for positively removing the 35 cleaned bobbin from its cleaning position.

6. In a filling replenishing loom, the combination of a bobbin receiver, a rotary bobbin cleaner, a rotary bobbin positioning device having a plurality of bobbin compartments 40 and located below the bobbin cleaner, and means for turning the bobbin positioning device on call for replenishment of filling to positively remove a cleaned bobbin and present another compartment for the reception 45 of a bobbin to be cleaned.

7. In a filling replenishing loom, the combination of a bobbin receiver, a bobbin positioning device in the bobbin receiver provided with a plurality of compartments each 50 to position a bobbin to be cleaned, a rotary bobbin cleaner above the bobbin positioning device to engage the filling between a discharged bobbin and the shuttle box, and means for moving the bobbin positioning device on call for replenishment of filling to 55

positively remove the cleaned bobbin and present another compartment for the reception of another bobbin to be cleaned.

8. A bobbin cleaner, comprising in combination a bobbin receiver, a bobbin positioning device provided with a plurality of compartments each to receive and position a bobbin to be cleaned of waste yarn, a rotary bobbin cleaner having a roughened yarn engaging surface positioned above the bobbin 70 positioning device, and means for moving the bobbin positioning device to positively move a cleaned bobbin from cleaning position and present another compartment for the reception of a bobbin to be cleaned of 75 waste yarn.

9. A bobbin cleaner, comprising in combination a bobbin receiver, a bobbin positioning device provided with a plurality of compartments each to receive and position a 80 bobbin to be cleaned of waste yarn, a rotary bobbin cleaner having a roughened yarn engaging surface positioned above the bobbin positioning device, means for moving the bobbin positioning device to positively move 85 a cleaned bobbin from cleaning position and present another compartment for the reception of a bobbin to be cleaned of waste yarn, and means for locking the bobbin positioning device from movement while a bobbin is 90 being cleaned.

10. A bobbin cleaner, comprising in combination a bobbin receiver, a bobbin positioning device provided with a plurality of compartments each to receive and position a 100 bobbin to be cleaned of waste yarn, a rotary bobbin cleaner having a roughened yarn engaging surface positioned above the bobbin positioning device, and a ratchet and pawl mechanism actuated on call for replenishment of filling for moving the bobbin positioning device to positively remove the cleaned bobbin from cleaning position and present another compartment for the reception of a bobbin to be cleaned. 105

11. A bobbin cleaner, comprising in combination a bobbin receiver, a bobbin positioning device provided with a plurality of compartments each to receive and position a bobbin to be cleaned of waste yarn, a rotary 110 bobbin cleaner having a roughened yarn engaging surface positioned above the bobbin positioning device, a guide for directing a bobbin to be cleaned into a compartment of the bobbin positioning device, and means for advancing the bobbin positioning device to positively move a cleaned bobbin from cleaning position and present another compartment for the reception of a bobbin to be cleaned as it is directed to said compartment by the bobbin directing guide. 115

12. In a filling replenishing loom, the combination of the change or transverse shaft, a bobbin receiver having a bobbin cleaner, a bobbin positioning device having compartment 120 125

- ments for holding bobbins to be cleaned that the filling may be engaged by the bobbin cleaner between the shuttle box and bobbin to be cleaned, and means actuated by the change or transverse shaft on call for replenishment of filling to advance the bobbin positioning device to positively remove the cleaned bobbin and present a compartment for the next bobbin to be cleaned.
- 10 13. In a filling replenishing loom, the combination of the change or transverse shaft, a bobbin receiver having a bobbin cleaner, a bobbin positioning device having compartments for holding bobbins to be cleaned that
- 15 the filling may be engaged by the bobbin cleaner between the shuttle box and bobbin to be cleaned, means actuated by the change or transverse shaft on call for replenishment of filling to advance the bobbin positioning device to positively remove the cleaned bobbin and present a compartment for the
- next bobbin to be cleaned, and a lock for holding the bobbin positioning device from movement during the intervals between filling replenishment. 25
14. A bobbin cleaner, comprising, in combination, a bobbin receiver, a rotary bobbin positioning device extending transversely of the receiver and having radially projecting wings constituting bobbin holding compartments, a bobbin cleaner above the bobbin positioning device to engage the filling leading from a bobbin in one of said compartments, and means for rotating the bobbin holding device at intervals to positively remove a cleaned bobbin from cleaning position and present another compartment for the reception of a bobbin to be cleaned. 30
- In testimony whereof, I have signed my name to this specification. 35

GEORGE H. WILLARD.
